UNITED STATES PATENT OFFICE.

ISAAC A. GORMON, OF RICHMOND, INDIANA.

BILLIARD-CUE TIP.

934,163.

Specification of Letters Patent. Patented Sept. 14, 1909.

Application filed April 28, 1909. Serial No. 492,753.

To all whom it may concern:

Be it known that I, ISAAC A. GORMON, a citizen of the United States, residing in Richmond, in the county of Wayne and State of Indiana, have invented a new and useful Billiard-Cue Tip, of which the following is a full, clear, and comprehensive specification, being such as will enable others skilled in the art to which the invention pertains to make and use the same with exactitude.

The object of this my present invention is to provide a billiard cue tip which will be neat and attractive in appearance, strong and durable in construction, easily operated and controlled, and which can be made and sold at a reasonable price.

The particular object I have in view is to produce a billiard cue tip by means of which, when attached to the cue proper, a resilient and cushioned stroke may be imparted to the balls, by which the physical exertion is reduced to the minimum, and by which more accurate plays may be made.

Other particular objects and specific advantages of my invention will appear in the course of the following specification, and that which is new and useful will be correlated in the appended claims.

The preferred manner of carrying out the principles of my invention in a practical manner, and that which in practice I have found to be highly efficient and practical, is shown most clearly in the accompanying drawings, in which—

Figure 1 shows my invention complete and in operative condition as attached to a cue. Fig. 2 is a central longitudinal section of the same. Fig. 3 is an isometrical detail view of the body portion of my invention. Fig. 4 is a cross sectional view, as taken on the line 4—4 of Fig. 2. Fig. 5 is a central longitudinal section of the casing or jacket. And Fig. 6 is a face view of the cushion.

Similar indices designate like parts throughout the several views.

In order that the invention and its operation may be more fully understood I will now take up a detail description thereof, in which I will set forth the invention as briefly and as comprehensively as I may.

In the drawings the letter A denotes the smaller end-portion of a cue, having a tenon a projecting out centrally therefrom in an axial direction.

Numeral 1 denotes the body member of my invention, the periphery thereof corre-

sponding with the periphery of the cue A. Extending centrally into one end of the body 1 is a cavity b in which may be tightly fitted and secured the tenon a, as indicated in Fig. 2.

Letters c and d denote two channels formed longitudinally of and on opposite sides of the body 1, same being identical with each other but oppositely disposed; these channels open at one end on each side of the mouth of the cavity b, as indicated in Fig. 3. The other end of each of said channels terminates in a rounded end, forming shoulders e and f, respectively, which are located about midway of the body 1, as shown in Figs. 2 and 3.

Numeral 2 denotes the casing, which is round in cross section, same being of a diameter such as to snugly surround the end portion of the cue A, and also surrounding the body 1 which is slidably endwise therein. Said casing 2 is of a length considerably greater than is the body 1, being adapted to extend therebeyond at either end thereof as shown in the drawings.

Located about midway of the length of the casing 2, preferably formed integral therewith, and extending into the interior thereof, are the two oppositely disposed lugs, 2' and 2'', they being formed round in cross section. Said lugs are of a diameter and extension such as to snugly fit in the respective channels c and d, and they are also adapted to fit the shoulders e and f. The inner periphery of the outer end portion of the casing 2 is provided with screw threads g as indicated.

Numeral 3 denotes the head, same being provided with a screw thread h formed around in its periphery, said threads h being adapted to engage with the threads g, as in Fig. 2. Attached on the outer face of the head 3 is the convex cap 4.

Numeral 5 denotes a cushion, formed of rubber, coil spring, or other resilient body, being of substantially the same diameter as is the head 3, and fitting the interior of the casing 2.

The device is adapted to be assembled as follows: Supposing that all of the parts to be disassociated with relation to each other. In order to assemble the device I first take the body 1 and insert it in the casing 2, to the position shown by the parts in Fig. 2, which manifestly will cause the lugs 2' and 2'' to enter the channels c and d, respectively. After the above the tenon a should be rigidly

secured in the cavity *b*, thereby connecting the body 1 to the cue A. I next place the cushion 5 inside the casing 2, bringing it in contact with the face of the body 1 as shown. 5 The head 3 may now be screwed into the outer end of the casing 2, bringing the inner face of the head 3 into contact with the cushion 5. It is preferable that the head 3 be screwed down quite tightly against the cushion, the latter pressing against the body, thereby causing the lugs to be brought tightly into contact with the shoulders *e* and *f*, which of course will retain the parts in position and prevent their inadvertent removal from the cue. 10 The cap 4 may be secured to the head 3 in any well known manner. It will now be apparent that if the cue be held in one's hands in the usual manner, and if an object, as a billiard ball, be struck 15 in the usual manner, that the impact received by the cap 4 will be absorbed by the cushion, the cap 4, the head 3, and the casing 2, having a movement independent of the cue A and the body 1.

20 25 It is apparent that the tension of the cushion may be adjusted to suit the individual player by turning said head to move it up or down, whereby the compression thereof on the cushion may be increased or diminished.

I desire that it be understood that various changes may be made in the several details of construction without departing from the spirit of my invention or sacrificing any of 30 the advantages thereof.

Having now fully shown my invention, the manner of its construction and operation, and the best means for carrying out the invention to me known at this time, what I 35 claim and desire to secure by Letters Patent 40 of the United States, is—

1. In combination with a billiard-cue, a tip comprising a body member connected to

the end of the cue, a head located at a distance from the body, cushioning means disposed between the body and the head, a casing inclosing said cushioning means, said head being threaded into the outer end of said casing and adapted to be rotated to adjust the compression of said cushioning means. 45

2. A billiard cue tip, comprising in combination a body rigidly connected to the end of a cue, a head located at a distance from the body, resilient cushioning means located 55 between the body and the head, a casing inclosing said resilient cushioning means same being removably connected to said head and slidably in an axial direction on the end portion of a cue, the compression of said resilient means being adapted to be adjusted by the rotation of said head. 60

3. A billiard cue tip, comprising a body member adapted to be rigidly secured to the small end of a cue and conforming therewith, said body member being provided with oppositely disposed channels formed in the sides and longitudinally thereof, the forward ends of said channels forming shoulders near the center of the body; a casing surrounding 70 said body, lugs extending inward from the inner wall of said casing and adapted to snugly operate in the respective channels therefor, a cushion located inside the casing and in contact with the forward end of said body, and a head secured in the forward end of said casing and contacting with said cushion. 75

In testimony whereof I have hereunto subscribed my name to this specification in the presence of two subscribing witnesses. 80
